HALL H. HOLDAWAY, OF LONG BEACH, CALIFORNIA, ASSIGNOR TO BYRON JACKSON CO., OF WEST BERKELEY, CALIFORNIA, A CORPORATION OF DELAWARE

ANTIFRICTION BEARING FOR DRILL PIPES

Application filed December 27, 1926. Serial No. 157,231.

My invention relates to well drilling equipment, and relates particularly to anti-friction bearing for drill pipe.

In the oil producing industry it is common practice to use rotary equipment which employs a rotary bit for sinking the hole. This rotary bit is attached to the lower end of a string of drill pipe which extends upward through the well to a point above the surface of the ground. The drill pipe is rotated by means of a rotary machine located on the floor of a derrick of the well. The drill pipe consists of stands of pipe which are connected together by tool joints. Each stand of pipe 10 is about eighty feet long and consists of four lengths of pipe which are attached together by ordinary sleeve couplings. When the drill pipe is withdrawn from the well it is broken at the tool joints. Wells are most always 15 crooked and for this reason the drill pipe, usually the tool joint portions thereof, will engage one side of the well casing which is installed in the well. The friction between the drill pipe and the well casing causes both of 20 them to wear. The greatest damage is done to the well casing and very often a hole is worn therein which will permit water to enter the well. This is very detrimental to the well since the water may mix with the oil and 25 form the objectionable emulsion. It is very difficult to discover water leaks and many cases are known where the well has been abandoned because the operators could not 30 find where the water entered.

It is an object of this invention to provide 35 an anti-friction bearing which may be placed on the drill pipe at various places, at the well, and after the parts of the drill pipe have 40 been assembled. The anti-friction bearing prevents the drill pipe or the well casing from being worn.

It is a further object of the invention to 45 provide an anti-friction bearing of the character mentioned in which the parts may be easily assembled.

Other objects and advantages of the invention will be made evident hereinafter.

Referring to the drawing in which I illustrate the invention:

Fig. 1 is a diagrammatic view illustrating the utility of the invention.

Fig. 2 is an elevational view of my invention in section and applied to a drill pipe.

Fig. 3 is an elevational view taken as indicated by the arrow 3 of Fig. 2, this view being partly sectioned.

Fig. 4 is a section taken on the line 4—4 of Fig. 2.

Fig. 5 is an enlarged fragmentary section 60 showing the means which permits the installation of balls of the bearing.

Fig. 6 is a fragmentary section similar to Fig. 5, but showing an insert of the invention 65 in place.

Fig. 7 is a perspective view of the insert.

Fig. 8 is an elevational view, partly sectioned, of another form of the invention.

Fig. 9 is a fragmentary section taken on the line 9—9 of Fig. 8.

Referring first to Fig. 1, the utility of the invention will be described. The numeral 11 represents a well which is being sunk by means of a rotary bit 12 which is secured to the lower end of a string of drill pipe 13. The string of drill pipe 13 is extended upward through the well 11 and is rotated by means of a rotary machine 14 located on the floor of a derrick 15. The drill pipe 13 consists of stands 17 which are joined together by tool 70 joints 18. In Fig. 1 a well casing 19 is placed in the upper part of the well 11. The well 11, as is quite common in the oil producing industry, is crooked so that the drill pipe would 75 ordinarily engage the well casing 19. Installed on the different stands of drill pipe 17 are anti-friction bearings 20 of the invention which prevent the drill pipe from engaging the well casing so that neither of these parts will be worn, all friction being taken by the 80 anti-friction bearings 20 of my invention.

The details of one form of my invention are illustrated in Figs. 2 to 7 inclusive, to which figures reference will now be had.

The invention has an inner race 25 which 95 is adapted to be placed around the drill pipe 13. The inner race 25 is formed from two parts 26 which are slightly less than semi-cylindrical. Edges 27 of the parts 26 engage each other, whereas, on the opposite side, 100

edges 28 are spaced apart so as to provide an inner groove or slot 29. The parts 26 are secured together by screws 30 as illustrated in the drawing. The inner race 25 has a number of annular ball channels 31 which are semi-cylindrical in cross-section. An insert 33, which is illustrated in detail in Fig. 7, is adapted to be extended into the groove 29 for filling it after the other parts of the bearing have been assembled. The insert 33 is provided with semi-cylindrical insert channels 34 which align with the channels 31 of the inner race 25, thus providing continuous ball channels for bearing balls 35 which operate therein. The insert 33 is provided with openings 36 at opposite ends thereof through which the screws 30 extend so that the insert is clamped to the parts 26.

Surrounding the inner race 25 is an outer one-piece race 39 which is provided with outer ball channels 40 which align with the inner ball channels 31. The outer race 39, as illustrated in Fig. 6, is provided with an axial groove 42 which is connected to the upper end thereof and which connects to each of the outer ball channels 40.

The anti-friction bearing is particularly designed so that the parts may be easily assembled, this assembly being as follows:

10 The parts 26 of the inner race 25 are placed around the drill pipe in the desired position, and the screws 30 are placed only at the side opposite from the groove 29. The other screws are not placed at this time. The outer 35 diameter of the inner race 25 is slightly greater than the outer diameter of the tool joint 18. This permits the internal diameter of the outer race 39 to be made large enough so that it can be extended over the tool joint 40 18 and into proper position around the inner race 25. The next operation is to install the bearing balls 35. The outer race is moved into such a position that the axial groove 42 aligns with the inner groove or slot 29 of the 45 inner race 25. This is illustrated in Fig. 5. It should be noted that the outer part of the inner groove 29 is diverged, as indicated at 45, so that the cross-section of the opening provided by the grooves 42 and 29 will receive the balls 35. The balls 35 are then dropped into the upper end of the opening provided by these channels and they fall downward therethrough, filling the various inner and outer channels 31 and 40. In case 50 any of the balls tend to stick in the grooves they may be forced into the channels by a slight rotation of the outer bearing member 39. After the balls have been assembled the insert 33 is installed in the inner groove 29 as 60 illustrated in the detail of Fig. 6. The remaining two screws 30 are then screwed into place so that these two sides of the inner race 25 and the insert 33 are secured rigidly to the drill pipe. This completes the assembly, and 65 the bearing is now ready for operation. When

the bearing of the invention is in the well and in the position indicated in Fig. 1 in contact with the well casing, the outer race engages the well casing and remains substantially stationary. The inner race rotates inside the outer race and the frictional contact between the races is taken by the bearing balls 35. I have found that my invention will prevent the well casing from being perforated by frictional engagement of the drill pipe 75 with it. Not only will there be no wear on the well casing but there will be no wear on the drill pipe itself.

One important feature of the bearing is that it may be assembled after the stands of 80 drill pipe have been assembled at the well. This is a desirable feature and makes it very convenient to replace worn bearings or to readjust the bearings when desired. The construction of the outer and inner grooves 42 85 and 29 and the insert 33 is an important part of the invention inasmuch as it permits an easy assembly of the bearing.

In Fig. 8 and Fig. 9 I show an alternative form of the invention. This form of the invention has an inner race 60 and an outer race 61. The inner race 60 may be made in two parts but is completely annular and provides annular channels 62 of semi-cylindrical cross-section. The outer race 61 provides annular channels 63 which are of semi-cylindrical cross-section and which are aligned with the channels 62. Balls 64 which operate in the channels 62 and 63 are inserted in place through ball entrances 66 formed in the outer race 61 in alignment with the outer channels 63. After the balls have been assembled, plugs 67 are placed in the ball entrances 66 and are secured in place as by welding indicated at 68. This form of the invention is 105 likewise very easy to assemble and may be installed on the drill pipe at the well after the drill pipe has been assembled.

I claim as my invention:

1. In an anti-friction bearing for drill pipe, 110 the combination of: an inner race having a number of ball channels, said inner race being adapted to surround a drill pipe and having a groove connected to all of said ball channels; an outer race adapted to surround said inner race, said outer race having ball channels arranged to align with said ball channels of said inner race, and said outer race having a groove connected to all of said ball channels of said outer race; balls in said ball channels, said balls being inserted through said grooves when they are aligned; and an insert for filling one of said grooves.

2. In an anti-friction bearing for drill pipe, 125 the combination of: an inner race having a number of ball channels, said inner race being adapted to surround a drill pipe and having a groove connected to all of said ball channels; an outer race adapted to surround said inner race, said outer race having ball channels ar- 130

ranged to align with said ball channels of said inner race, and said outer race having a groove connected to all of said ball channels of said outer race; balls in said ball channels, 5 said balls being inserted through said grooves when they are aligned; and an insert for filling one of said grooves, said insert having insert channels adapted to align with said ball channels.

10 3. In an anti-friction bearing for drill pipe, the combination of: an inner race having a number of ball channels, said inner race being adapted to surround a drill pipe and having a groove connected to all of said ball channels; an outer race adapted to surround said inner race, said outer race having ball channels arranged to align with said ball channels of said inner race, and said outer race having a groove connected to all of said ball channels 15 of said outer race; balls in said ball channels, said balls being inserted through said grooves when they are aligned; and an insert for filling said groove of said inner race.

4. In an anti-friction bearing for drill pipe, 25 the combination of: an inner race having a number of ball channels, said inner race being adapted to surround a drill pipe and having a groove connected to all of said ball channels; an outer race adapted to surround said inner race, said outer race having ball channels arranged to align with said ball channels of said inner race, and said outer race having a groove connected to all of said ball channels of said outer race; balls in said ball channels, 30 said balls being inserted through said grooves when they are aligned; and an insert for filling said groove of said inner race, said insert having insert channels adapted to align with said ball channels.

40 5. In an anti-friction bearing for drill pipe, the combination of: an inner race having a number of ball channels, said inner race being adapted to surround a drill pipe, said inner race being made in two parts, said 45 parts not contacting along one edge, thus forming a groove connected to all of said ball channels; an outer race adapted to surround said inner race, said outer race having ball channels arranged to align with said ball channels of said inner race, and said outer race having a groove connected to all of said ball channels of said outer race; balls in said ball channels, said balls being inserted through said grooves when they are aligned; 50 and an insert for filling one of said grooves.

6. In an anti-friction bearing for drill pipe, the combination of: an inner race having a number of ball channels, said inner race being adapted to surround a drill pipe, said inner race being made in two parts, said parts not contacting along one edge, thus forming a groove connected to all of said ball channels; an outer race adapted to surround said inner race, said outer race having ball channels 55 arranged to align with said ball channels of

said inner race, and said outer race having a groove connected to all of said ball channels of said outer race; balls in said ball channels, said balls being inserted through said grooves when they are aligned; and an insert for filling one of said grooves, said insert having insert channels adapted to align with said ball channels. 70

7. In an anti-friction bearing for drill pipe, the combination of: an inner race having a number of ball channels, said inner race being adapted to surround a drill pipe, said inner race being made in two parts, said parts not contacting along one edge, thus forming a groove connected to all of said ball channels; an outer race adapted to surround said inner race, said outer race having ball channels arranged to align with said ball channels of said inner race, and said outer race having a groove connected to all of said ball channels of said outer race; balls in said ball channels, said balls being inserted through said grooves when they are aligned; and an insert for filling said groove of said inner race. 85

8. A combination as defined in claim 1 in which the outer part of said groove of said inner race is diverged.

9. An anti-friction bearing for protecting a well casing from a rotary string, comprising an inner race adapted to surround the string and provided with circumferential ball channels, an outer race adapted to surround the inner race and provided with ball channels positioned to align with the ball channels of the inner race, the outer race being sufficiently smaller than the interior of the well casing to provide for the free passage of the flushing water and the detritus, each of the races provided with a groove connected to all of the ball channels thereof, balls in the channels, said balls being inserted through said grooves when they are aligned, and an insert for filling one of said grooves. 95

10. An anti-friction bearing for protecting a well casing from a rotary string, comprising an inner race adapted to surround the string and provided with circumferential ball channels, an outer race adapted to surround the inner race and provided with ball channels positioned to align with the ball channels of the inner race, the outer race being sufficiently smaller than the interior of the well casing to provide for the passage of the flushing water and the detritus, the races 110 providing between them a ball-inducting opening communicating with all of the ball channels, balls in the channels, said balls being inserted through said opening, and an insert in the opening to prevent the balls discharging therefrom. 115

In testimony whereof, I have hereunto set my hand at Los Angeles, California, this 17th day of December, 1926.

HALL H. HOLDAWAY. 125
